UNITED STATES PATENT OFFICE

2,254,513

RAILWAY TRUCK STRUCTURE

Edwin G. Busse, Chicago, Ill., assignor to Chicago Railway Equipment Company, Chicago, Ill., a corporation of Illinois

Application March 20, 1940, Serial No. 325,034

15 Claims. (Cl. 188—212)

The invention relates to railway rolling stock and more particularly to the mounting of brake beams upon the truck frame and the guiding of the beams in their movement to and from the wheels.

The usual support for the brake beam on the truck frame comprises a swinging link suspended from a side frame bracket above the beam and pivotally engaging the brake head. This device will not in itself guide the brake beam, i. e., maintain its desired angular relation to the wheel tread, throughout the movement of the brake beam to and from the wheels. Usually other devices are provided for this purpose, the same being carried by the truck side frame or the spring plank or the bolster.

One of the objects of the invention is to simplify the support and guiding of the beams.

Another object of the invention is to facilitate the application and removal of the beams to and from the truck for repair or replacement.

Another object of the invention is to support and guide the ends of an A. A. R. standard truss type brake beam on the side frames by brackets on the side frames adjacent to the ends of the brake beams without interfering with the usual tensioning nuts projecting beyond the brake heads.

The present invention utilizes some of the features more generally disclosed and covered in copending applications filed by the same inventor January 6, 1938 and bearing Serial Nos. 183,601 and 183,602, respectively. Since the filing of the present application the first-mentioned copending application has matured into Patent No. 2,197,785, dated April 23, 1940, and the second-mentioned copending application has matured into Patent No. 2,226,551, dated December 31, 1940.

The general objectives referred to above and other more specific objects, as will appear hereinafter, are attained by the structure illustrated in the accompanying drawings in which—

Figure 1 is a fragmentary top view and horizontal section through portions of the side frames of a railway truck showing the adjacent portions of two truck wheels and the brake beam mounted on the side frames and applied to the wheels. The section portions of the figure are taken approximately on the lines 1—1 of Figure 2.

Figure 2 is a vertical transverse section through the truck side frames and shows the brake beam and wheels in elevation.

Figure 3 is a side elevation of the major portion of the truck with a part of the side frame

broken away to illustrate the structure more clearly, and showing bracket parts sectioned as indicated by the line 3—3 in Figure 2.

Figures 4, 5, 7, 9, 11, 13, 14, 15 and 16 are vertical transverse sections through portions of truck side frames and illustrating parts associated therewith, and each embodying a different form of the beam supporting and guiding structure to which the present application is directed.

Figures 6, 8, 10 and 12 are horizontal sections taken on the corresponding section lines of Figures 5, 7, 9 and 11, respectively.

Figures 1, 2 and 3 show the more important elements of a familiar type of railway four-wheel truck which includes wheels 4, side frames 2, springs 3 carried directly on the side frames, or on a spring plank (not shown) connecting the side frames, and a bolster 4 supported on springs 3 and projecting through the window 5 between the top and bottom chords 6 and 7 of the side frame and its upright columns 8. A truss type brake beam is provided for the wheels and includes a compression member 9, the ends of which enter and seat the brake heads 10, a strut 11, a tension rod 12 with its ends extending through the brake heads and threaded for the application of tensioning nuts 13 seated on the outer faces of the brake heads.

The right hand side frame, shown in Figures 1 and 2, is provided with flanges or guides 15 adjacent to the ends of the brake beam and spaced vertically to receive between them cooperating flanges or ears 16 provided on the outer face of the adjacent brake head 10. Flanges 15 and 16 extend a substantial distance longitudinally of the truck and are inclined to the horizontal, as best shown in Figure 3, and support and guide the brake beam in its movement to and from the wheels.

Since it is necessary to apply the beams to the truck after the truck has been assembled and to remove the beams from the truck at intervals without disassembling the other parts of the truck, and since the clearance between the wheels and the bolster and bolster spring, and spring plank if the same is present, will not permit rearward movement of the beam to clear supporting flanges such as are shown at 15, it is desirable to provide a supporting member at the opposite side of the truck which may be shifted into a functioning position underlying the end of the brake beam, or into a position in which it clears the brake beam end and permits it to be dropped, as indicated by the broken lines B in Figure 2, whereupon the beam may be moved

lengthwise away from flanges 15 and removed from the truck. Accordingly, the beam supporting member at the left hand side of the truck is movably mounted upon the left hand side frame.

In Figure 2 this member comprises a bracket 17 opposite to the end of the beam with spaced ears 18 projecting through an opening 19 in the side wall of the frame and pivotally connected by rivets 20 to lugs 21 on the frame side wall. The axis of rivets 20 extends longitudinally of the truck and, as shown, in substantially parallel to the top face of bracket 17 which supports the beam. An intermediate ear 22 on bracket 17 projects upwardly and inwardly between lugs 23 on the side frame and is detachably secured thereto by a pin 24 which may be removed readily by a workman at the side of the truck to permit bracket 17 to swing downwardly to the broken line position indicated at 17a, whereupon the brake beam may be dropped and removed as previously described. Preferably guides 15 and bracket 17 have their rear ends flanged to limit the movement of the beam away from the wheels.

A depending lug L on bracket 17 seats a rubber pad R which is thrust against the side frame wall when pin 24 is inserted through ear 22 and lugs 23, and this pad cushions play between the bracket and frame.

While the adaptability of the above described structure for its intended purpose is evident, it will be noted that the brake beam may follow A. A. R. standards in every respect and, if desired, the brake head may be provided with pockets for receiving the usual hanger suspended from the upper part of the side frame. Obviously both sides of the truck may be equipped with a pivoted bracket for supporting the beam if it were preferred not to have different side frame constructions, or if for any other reason it was desired to provide a shiftable bracket at both ends of the beam.

Figure 4 illustrates a construction corresponding to that just described except that the bracket 25 is below the level of its pivot 26, and the holding pin 27 passes through an ear below said level instead of through an ear above said level. With this arrangement the beam engaging portion of the bracket swings away from the beam more rapidly than in the form previously described.

Figures 5 and 6 illustrate a form of the invention in which the beam supporting bracket 30 swings about a vertically disposed pivot pin 31 seated in horizontal lugs 32 on the truck side frame 33. Bracket 30 slides over the upwardly facing edge 34 of the opening in the frame wall and is retained in its functioning position by removable bolt 35 which is readily accessible from the outer side of the truck.

Figures 7 and 8 illustrate another form of the invention in which the beam supporting bracket is not pivoted to the side frame but comprises an L-shaped member having a horizontal leg 40 and a vertical leg 41, the horizontal leg sliding over the upwardly facing edge of the opening in the side frame and the vertical leg being movable between two upright lugs 43 on the side frame. A pin 44 may be inserted through lugs 43 to prevent the retraction of legs 40-41. Preferably a spring 45 is compressed between leg 41 and the opposing face of the frame side wall 46, and this spring will hold the bracket against play in the frame. Upon removal of pin 44, the

bracket may be withdrawn to the dotted line position indicated to facilitate the dropping of the adjacent end of the brake beam.

Figures 9 and 10 illustrate a similarly shaped angular bracket 50, the upright leg of which is bolted directly to the side frame wall 51 by bolts 52 having nuts 53 which may be removed through the opening in the outer side of the truck to permit the bracket to be slid inwardly as indicated. Preferably rubber elements 54 are inserted between wall 51 and the upright leg of the bracket to prevent play between the parts.

Figures 11 and 12 illustrate another form of the invention in which the bracket 55 rests upon an upwardly facing shelf 56 in the side frame 51. Detachable bolts 58 pass through an opposing flange 59 and bracket 55 to retain the latter in projected functioning position. Preferably shelf 56 is slotted to receive a boss 60 on the bottom of bracket 55, and this boss will limit the transverse movement of the bracket through the frame.

In Figure 13 the inwardly extending shelf on the frame is omitted and the bracket 61 has a return bend 62 on its inner end to overlie the lug 63 on the side frame to contribute to the stable support of the bracket. Detachable bolt 64 holds the bracket in functioning position.

In Figure 14 the bracket 65 is slotted at 66 to receive a bolt 67 which limits the left hand movement of the bracket to prevent its disassembly from the side frame. Bolts 68 are inserted through flanges 69 and 70 to hold the bracket in functioning position.

In Figure 15 the bracket 76 has its inner end 76 turned downwardly and bolted to the frame side wall 77.

In Figure 16 bracket 80 has a single upstanding ear 81 receivable between two upright lugs 82 on the side frame wall 83. A horizontally disposed pin 84 holds the bracket in functioning position.

Each of these forms embodies one or more features which may be found advantageous for one reason or another, according to the particular conditions encountered, and those working in the art will likely make other variations in the details of the structure without departing from the spirit of the invention, and the exclusive use of such modifications as come within the scope of the invention is contemplated.

What is claimed is:

1. In a railway truck, wheels, a side frame, a brake beam, and a support for said brake beam comprising a bracket pivoted to said side frame and movable on its pivot into and out of functioning position in which it underlies a head on said brake beam and thereby supporting the beam and having its head engaging surface disposed at an angle to the horizontal to maintain the desired angular relation between the brake beam and the adjacent wheel during the application and release of the brake.

2. In a railway truck, wheels, a side frame having the usual top, bottom and upright elements forming an opening in said frame between each of said upright elements and the adjacent wheel, a brake beam, and a device for supporting said beam comprising a bracket mounted on said side frame adjacent the end of the beam and extending inwardly from said side frame and shiftable on its mounting into and out of functioning position, and a detachable element for securing said bracket in place, said element being accessible

through said opening to a workman at the outer side of said side frame.

3. A structure as described in claim 2 in which the portion of the side frame adjacent the end of the brake beam includes an upright wall extending longitudinally of the truck, and the beam supporting bracket projects through said wall and is secured at the side of said wall facing away from the beam.

4. A structure as described in claim 2 in which the portion of the side frame adjacent the end of the brake beam includes an upright wall extending longitudinally of the truck, and the beam supporting bracket projects through said wall and is pivoted to the side frame by a pin seated in said side frame at the side of said wall facing away from the beam.

5. In a railway truck, wheels, a brake beam therefor, a side frame including an upright wall extending longitudinally of the truck adjacent to the end of said brake beam, and a support for said beam slidable on said wall transversely of the truck into and out of functioning position.

6. In a railway truck, wheels, a brake beam therefor, a side frame including an upright wall extending longitudinally of the truck adjacent to the end of said brake beam, and a member slidable through said wall transversely of the truck into and out of functioning position and forming the sole support for the adjacent end of the brake beam, said member, at one end of its sliding movement, providing for the dropping and removal of the beam from the truck.

7. In a railway truck, wheels, a brake beam therefor comprising a compression member, brake heads seated thereon, a strut, a tension member extending over said strut and through said heads, and nuts threaded on the ends of said tension member and seated on the outer faces of said heads, and a side frame having brackets engaging downwardly and upwardly facing elements on said heads for supporting and guiding the beam, said brackets being spaced apart to clear the corresponding tension member nut, at least one of said brackets being movable on said side frame away from said beam to provide for the dropping of the latter when it is to be removed from the truck.

8. In a railway truck, wheels, side frames at opposite sides of the truck, a brake beam extending between said side frames, one of said side frames having integral means for supporting and guiding the adjacent end of said beam, and the other of said side frames having a bracket movably mounted thereon to shift into a position beneath the adjacent end of said brake beam to support and guide the same in its movement towards and away from said wheels, or to shift into a more remote position to provide for the dropping of the adjacent end of the beam and the subsequent movement of the beam lengthwise and away from said means to remove the beam from the truck.

9. In a railway truck, wheels, a side frame, a brake beam with heads and shoes, a device movably mounted on said side frame to shift into and out of a functioning position in which it under-

lies a portion of one of said heads and extends longitudinally of the truck to guide the beam as its shoes are applied to the wheels, an element for holding said device in functioning position, and yielding means compressed between said frame and device when said element is in place to cushion play between the assembled parts.

10. In a railway truck, wheels, a side frame including an upright web extending longitudinally of the truck, a brake beam movable to and from said wheels, and a device for supporting said beam during such movement and comprising a member mounted on said web at the side thereof facing outwardly of the truck, said member projecting through said web to engage said beam, said member being retractable through said web, without being disassembled from the side frame, to facilitate dropping of the adjacent end of the brake beam when the latter is to be removed from the truck.

11. A structure as described in claim 10 in which the beam supporting member is pivoted on the side frame web and is movable on its pivot through said web into and out of functioning position, there being releasable means for holding said member in functioning position.

12. In a railway truck, wheels, a side frame, a brake beam extending transversely of the truck with an end portion projecting into the space between the vertical planes of the opposing faces of said frame and the adjacent wheel, a member mounted on said side frame and movable thereon, without being disassembled therefrom, into and out of a functioning position in which it projects into said space and underlies said brake beam end portion, and readily detachable means for holding said member in said position.

13. A truck structure as described in claim 12 in which the beam and the supporting member have co-acting faces inclined to the vertical longitudinally of the truck to maintain the desired angular relation between the beam and the adjacent wheel in its movement to and from the wheel as the brakes are applied and released.

14. A truck structure as described in claim 12 which includes a pivot element maintaining the assembly of the side frame and the beam supporting member, and the readily detachable means cooperates with said pivot element to support the device in functioning position.

15. In a railway truck, wheels, a side frame, a brake beam, a member mounted on said side frame opposite to the end of the beam and forming an individual support and guide for the end of the beam in its movement to and from the wheels, the mounting of said member on the frame including a pivot element, the axis of which is disposed longitudinally of the truck, said member being movable about said element upwardly into functioning position and downwardly into a position in which it clears the adjacent end of the beam to accommodate the application and removal of the latter to and from the remainder of the truck, and manually detachable means for holding said member in functioning position.

EDWIN G. BUSSE.
